MOLDED PULP CARTON

Lile H. Brown, Thorndike, Mass., assignor to
 Shellmar Products Corporation, Chicago, Ill., a
 corporation of Delaware

Application March 24, 1947, Serial No. 736,791

3 Claims. (Cl. 229—15)

1

The present invention relates to improvements in molded pulp cartons of the cellular type suitable for carrying eggs, and has as a general object the provision of such a carton of the 2 x 6 style having adequate egg carrying space and of a size to fit into a standard 30 dozen egg case or its equivalent. Such a carton has long been desired, but limitations imposed by the molding process and functional requirement of the egg trade have made the development of a commercially acceptable carton a problem.

A principal object of this invention is to provide a molded pulp carton having a cellular arrangement which dimensionally meets the trade needs, provides room for large eggs, protects against breakage, compensates for the reduced transverse internal space resulting from the tapering of the sides of a carton and nests closely enough for shipping purposes.

Another object is the provision of a molded pulp carton having two longitudinal rows of cells, the corresponding cells in each row being staggered or offset to allow the eggs of one row to lie in between the eggs of the other row, thereby enabling closure of the carton cover even when a large egg is placed in the carton.

A further object is to construct a carton of the type described which will accommodate long and thick eggs and still be of such dimensions as to fit into a standard egg case.

These and other objects will be evident from the following description and the drawings, in which:

Fig. 1 is a plan view of the carton shown with its cover in opened position;

Fig. 2 is an end view of the carton in partially closed position showing the positioning of eggs; and

Fig. 3 is a sectional view taken along line 3—3 of Fig. 1, showing the carton closed.

A standard egg case of the thirty dozen type has two compartments of approximately one square foot area on each side of a central partition. Customarily, eggs are shipped in these cases to the packer, being disposed in the case in tiers of flats and fillers. The eggs are candled by the packer and placed in 2 x 6 cartons, which are then returned to the case for shipment to retail outlets. Since the cartons are packed three across in each compartment of the case and in five vertically disposed layers, the limitations as to size of the cartons are approximately as follows: height 2 1/2 inches, width 3 3/8 inches, and length 11 3/4 inches. It is better that the cartons be slightly under the theoretical dimensions of the case, since the latter often is warped. Thus,

10 a well-known 2 x 6 paperboard carton now on the market has a length of only 11 3/8 inches.

One of the requirements of the pulp molding process is that the walls of an article be tapered so that it can be withdrawn from the forming die, and also to permit the articles to be shipped in nested relation. Thus, as shown in the drawings, the cover of the present carton has a flat top 10 and outwardly and downwardly tapered front and rear walls, 11 and 12, respectively. The cover is of generally parallelogram shape with outwardly tapered end walls 13 and 14, as hereinafter described in detail, and two marginal cover-locking tabs 15 are integrally connected to the front wall 11, these being adapted to interlock with the bottom section, as will also be described. The rear wall 12 is hinged to the bottom section of the carton along a line 16.

It will be noted that the top 10 of the carton is more narrow than the width of the carton along its middle, this being a condition imposed by the tapered walls. As a result, the transverse area internally of the cover reduces toward the top, i. e., there is less transverse egg carrying space in the cover than at the center of the carton. Since eggs are packed in a carton with their large end up, a carton having a cover of sufficient volume to accommodate large eggs positioned directly across from each other in the transverse direction may be unduly wide at the center of the carton, or, if the carton is narrow enough to fit into a 30 dozen case, it will have inadequate egg carrying space in the cover.

The bottom section of the carton shown in the drawings is designed to provide adequate transverse space in the cover of the carton without undue width. The bottom section has two longitudinally extending rows of egg cells each including a bottom 17 from which upwardly tapered walls extend. These walls include outer walls 18, inwardly inclined cover walls 19 on each side of the outer walls, side walls 20 adjoining the corner walls, and centrally tapered, transversely angled partition-forming walls 21. Each of the cells save those at an outermost end of each of the rows has an inner wall 22 joining walls 21. In said outermost cells the walls 21 converge and meet.

It will be noted that the cells of each row adjoin each other along the reduced space represented by the upwardly merging and meeting walls 20. Walls 20 have greater taper than the other walls of the bottom and merge somewhat below the tops of said other walls.

Between the upper margins of adjacent walls 19 are triangular platforms 23.

Along the center of the carton the walls 21 and 22 merge together to form a longitudinal partition of zig-zag shape. The cells of the rear row are positioned in longitudinally staggered relation with respect to the cells in the front row, that is, the centers of the cells in one row are opposite the lines of merger of the cells in the other row. Furthermore, by the zig-zag formation of the longitudinal partition, the cells of one row are laterally nested or inset into or between adjoining cells of the other row.

As shown in Fig. 3, the walls 21 and 22 are of less height than the outer walls of the cells, but of greater height than the merging side walls 20. At their tops, walls 21 and 22 are joined by horizontal, triangular platforms 24 which lie laterally abreast a cell in one row and between adjacent cells in the other row. Platforms 24 are thus successively positioned oppositely and staggered along the longitudinal partition.

Between two sets of cells, and at longitudinally spaced positions opposite the cover-locking hooks 15, the front side of the carton is provided with hook-receiving openings 25 which function in the manner shown in Fig. 3 to receive said hooks and retain the cover in closed position.

Along the front wall of the bottom section is joined a cover-bracing flap 26 which normally extends outwardly as shown in Fig. 1. It preferably is joined to the bottom section along a weakened hinge line to facilitate bending. It will be noted that this cover bracing flange backs up the openings 25 and aids in strengthening the sides of the latter so as to make it more difficult to displace hooks 15 inadvertently from their engagement with the openings.

In utilizing the carton, eggs are placed in the cells in the manner shown in Fig. 2. These eggs are staggered and an egg in one row will be able to extend into the space between eggs in merging cells of the other row, thus taking advantage of the round shape of the eggs and cells to provide transverse space in the carton. Lacking this staggered positioning, in the case of large eggs the width of the cover is not great enough to accommodate the eggs without undue distortion of the cover or breakage of the eggs.

In closing the cover, the flange 26 is rotated upwardly and inwardly to a position within the cover, and the cover is rotated over into the position shown in Fig. 3. The hooks 15 are then pressed into the openings 25 from the outside of the cartons. If there are large eggs in the carton, closure of the tapered cover tends to press the tops of the eggs toward the center of the carton; that is, they tend to lean over toward the opposite row of eggs, and since they can be accommodated in the space between adjacent eggs in said opposite row, there is less tendency for them to be crushed than where the eggs in the two rows are oppositely positioned. Also, even though eggs in the opposite rows come in contact, the staggered disposition places their contact point in a tangential line at an angle to the transverse line of application of crushing force, hence reduces the tendency for breakage.

As the eggs lean over (Fig. 2) their longitudinal axis is at an angle, and therefore, the eggs also occupy less vertical space in the carton, which is of particular value in the case of long eggs. Thus the staggered positioning of the merging cells provide for both transverse and vertical space in the carton.

By arranging the cells in staggered relation,

the ends of the carton may be of the angular shape shown in Fig. 1. When the covers of the cartons are closed and the cartons are placed in a standard egg case in side-by-side relation, these angular ends provide hand openings by which the cartons may be grasped and removed without difficulty. The angular ends furthermore provide anchor or guide openings by which a stack of empty nested cartons may be held and displaced.

The extent of the stagger of the cells will depend upon such factors as the amount of room it is desired to gain transversely of the carton and the distance between cell centers in each row. Thus, for a carton of the same overall length as that shown in the drawings, but with cells which are wider spaced, less than a full stagger will be desired.

The above described carton has the advantage that, when the cartons are crated in a 30 dozen carton, the cartons of alternate layers are at right angles and in closing relation, the majority of eggs in any layer will be so positioned that the vertical axis thereof does not coincide with the vertical axis of the corresponding egg in the layer therebeneath. Thus direct transmission of vertical crushing stress is minimized.

The particular shape of the carton cells and the wall structure may be changed variously from the form shown in the drawings. For instance, provision may be made for divisibility of the carton into half dozen sizes. All such modifications are intended to be included in the appended claims.

I claim:

1. A molded paper pulp carton comprising cover and bottom sections of elongated generally parallelogram-shaped outline in plan, said sections being laterally enclosed around opposed side and end margins thereof and being integrally hinged to one another along one longitudinal side margin to bring the sections into vertical register in the closed condition of the carton, said bottom section being provided with internal upstanding formations, all of height less than that of said bottom section margins, arranged to subdivide the same into parallel rows of inclined wall cells which are in staggered, longitudinally and transversely nested relation to one another, whereby the respective axes of eggs disposed in adjoining longitudinally extending rows may readily be disposed in upwardly convergent angular relationship by the transverse overlapping of the rounded inner surfaces of the eggs, and a flange of substantial area integrally connected to the free margin of said bottom section and disposed, in said closed condition, in upright, vertically bracing relation to said cover section within the free margin of the latter, said flange at one end thereof longitudinally over-extending the corresponding end of the opposite, hinged side margin of the bottom section to support the cover section in this zone.

2. A molded pulp carton comprising cover and bottom sections of elongated generally parallelogram-shaped outline in plan, said sections being laterally enclosed around opposed side and end margins thereof and being integrally hinged to one another along one longitudinal side margin to bring the sections into vertical register in the closed condition of the carton, said bottom section being provided with internal upstanding formations, all of height less than that of said bottom section margins, arranged to subdivide the same into parallel rows of inclined wall cells

which are in staggered, longitudinally and transversely nested relation to one another, whereby the respective axes of eggs disposed in adjoining longitudinally extending rows may readily be disposed in upwardly convergent angular relationship by the transverse overlapping of the rounded inner surfaces of the eggs, and a flange of substantial area integrally connected to the free margin of said bottom section and disposed, in said closed condition, in upright, vertically bracing relation to said cover section within the free margin of the latter, said flange at one end thereof longitudinally over-extending the corresponding end of the opposite, hinged side margin of the bottom section to support the cover section in this zone, the ends of said bottom section having inwardly extending abutments engageable by the cover section ends to prevent vertical telescoping of the sections in these zones.

3. A molded paper pulp carton comprising cover and bottom sections of elongated generally parallelogram-shaped outline in plan, said sections being laterally enclosed around opposed side and end margins thereof and being integrally hinged to one another along one longitudinal side margin to bring the sections into vertical register in the closed condition of the carton, said bottom section being provided with internal upstanding formations, all of height less than that of said bottom section margins, arranged to subdivide 30

the same into parallel rows of inclined wall cells which are in staggered, longitudinally and transversely nested relation to one another, whereby the respective axes of eggs disposed in adjoining longitudinally extending rows may readily be disposed in upwardly convergent angular relationship by the transverse overlapping of the rounded inner surfaces of the eggs, and a member of substantial area integrally hinged to the other longitudinal side margin of said bottom section and disposed, in said closed condition, in upright, vertically bracing relation to said cover section within the free margin of the latter.
